UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,378,938.

Specification of Letters Patent. Patented May 24, 1921.

Application filed September 25, 1916. Serial No. 122,011.

To all whom it may concern:

Be it known that I, HENRY P. CLAUSEN, a citizen of the United States, residing at Mount Vernon, in the county of Westchester and State of New York, have invented certain new and useful Improvements in Telephone-Exchange Systems, of which the following is a full, clear, concise, and exact description.

10 This invention relates to telephone exchange systems, its object being the production of improved signaling means for such systems.

In accordance with a feature of this invention, should the incoming end of a trunk circuit be connected with a busy line, a signaling device will be operated to furnish a signal indicating that fact.

More specifically stated, a calling supervisory lamp associated with a cord circuit connected with the trunk circuit and a supervisory lamp associated with the trunk circuit are lighted intermittently or periodically whenever the trunk circuit is connected with a busy telephone line, whereby a distinctive signal is furnished both operators.

For a more complete understanding of this invention, reference should be had to the following description taken in connection with the drawing in which is shown a calling telephone line A terminating at one central office, a called telephone line B terminating at another central office, the calling line being connected to a cord circuit C, which in turn may be connected to a trunk circuit D for establishing connections with the called line B. It is to be understood that a number of telephone lines similar to A and B terminate at the respective central offices, that there are also at each central office a number of cord circuits similar to C, that a number of trunk circuits similar to D extend between the central offices, and that each telephone line is multiplied throughout a number of operators' positions, as is the usual practice. For the sake of simplicity, however, only two telephone lines, one cord circuit and one trunk circuit are illustrated in the drawing. It is believed that this invention will be fully understood from a description of the operation of the system shown in the drawing, and it will be so described.

Assuming that the operator at whose position cord circuit C is located has been ad-

vised that the subscriber on the connected calling line A desires to be connected with subscriber B whose line terminates in another central office, the operator at the originating central office will communicate the 60 number of the desired line to the operator at the terminating central office over a call wire circuit (not shown) and will receive a trunk assignment. Assuming that the trunk circuit D has been assigned, the operator at the originating office inserts the calling plug of the cord circuit C into the jack of the trunk circuit D, whereupon calling supervisory lamp 5 will be lighted and 65 relay 6, bridged across the outgoing end of the trunk circuit, will be operated. Since the left-hand winding of relay 6 is of high 70 resistance, supervisory relay 22 in the cord circuit does not now operate. Upon the operation of relay 6, lamp 7 at the incoming 75 end of the trunk circuit will be lighted over a circuit from battery through the normal contact of relay 8, lamp 7, contact of relay 6 and lower normal contact of relay 9 and resistance 10 to ground. The lighting of 80 this lamp will indicate to the terminating operator that connection has been made with the proper trunk circuit.

The terminating operator will thereupon, after testing B's line and finding it idle, insert the plug of the trunk circuit D into a jack associated with B's line, whereupon relay 9 will be operated over a circuit from battery through the normal contact of relay 8, lamp 7, winding of relay 9, sleeve contacts 90 of the plug and jack and the winding of cut-off relay 15 to ground. The operation of relay 9 causes the operation of slow-operating ringing relay 16 over a circuit from battery through the winding of relay 16, 95 normal contact of relay 17, contact of tripping relay 18, lower alternate contact of relay 9, contact of relay 6, winding of relay 9, sleeve contacts of the plug and jack and the winding of cut-off relay to ground. The 100 winding of ringing relay 16 is now bridged in parallel with the lamp 7 and effaces this lamp. The operation of ringing relay 16 connects a source of ringing current 19 through the winding of tripping relay 18 to 105 the called line for operating the call bell at the station connected with the line. The operation of the ringing relay 16 also causes the operation of relay 14 over a circuit from battery through the winding of relay 14, 110

lower alternate contact of ringing relay 16 and upper alternate contact of relay 9 to ground. Relay 14, in operating, establishes a locking circuit for itself through its alternate contact.

In response to the operation of the call bell, subscriber B removes his receiver from the switchhook, causing the operation of tripping relay 18, whereupon winding 20 of relay 17 is included in circuit with the ringing relay 16. Relay 17 thereupon operates and establishes a locking circuit for itself from battery through the left-hand alternate contact and winding 20 of relay 17, lower alternate contact of relay 9, contact of relay 6, sleeve contacts of the plug and jack and the winding of cut-off relay 15 to ground. Winding 20 of relay 17 is now substituted for the winding of ringing relay 16 and the lamp 7 remains effaced. The closure of the left-hand alternate contact of relay 17 establishes a short circuit for the ringing relay 16 which thereupon releases, disconnecting the source of ringing current from the called line. The release of ringing relay 16 permits the operation of supervisory relay 21, which, in operating, completes the circuit for the right-hand winding of relay 6 which is thereupon placed in parallel with the left-hand winding and reduces the resistance of the circuit including the supervisory relay 22, permitting an increased flow of current through the supervisory relay 22 which thereupon operates to efface the calling supervisory lamp 5, indicating to the operator at the originating central office that the called party has answered.

Upon completion of the conversation, the subscribers restore the receivers to the switchhooks, whereupon supervisory relay 21 is released, opening the circuit through the right-hand winding of relay 6. Supervisory relay 22 in the cord circuit C is thereby released, causing the supervisory lamp 5 to light to furnish a disconnect signal. Upon the removal of the calling plug of the cord circuit C from the jack of the trunk circuit D, relay 6 releases opening the shunt circuit about the lamp 7, whereupon the lamp lights to furnish a disconnect signal to the terminating operator. The terminating operator, observing the lighted condition of lamp 7, thereupon removes the plug from the jack of B's line, whereupon all apparatus associated with the trunk circuit will be returned to normal position.

Assuming that the terminating operator disregards the usual busy test signal or does not make the test and inserts the plug of the trunk circuit into a jack of B's line at the time this line is busy. The relay 9 operates, as before described, and upon its operation, supervisory relay 21 operates over the line circuit, the receiver of the station 65 on that line being off the switchhook. Re-

lay 21, in operating, connects the right-hand winding of relay 6 in parallel with the left-hand winding, thereby decreasing the resistance in circuit with relay 22 which operates to efface the supervisory lamp 5, 70 which remains effaced for only a short time, as will hereinafter more fully appear. The operation of relay 21 also causes the operation of relay 17 over a circuit from battery through upper alternate contact of relay 21, 75 winding 25 and normal contact of relay 17, normal contact of tripping relay 18, lower alternate contact of relay 9, contact of relay 6, winding of relay 9, sleeve contacts of the plug and jack and the winding of cut-off relay 15 to ground. Relay 17, in operating, establishes a locking circuit for itself through its left-hand alternate contact and winding 20 thereof, and in addition, causes the operation of relay 8 over a circuit from 80 battery through the winding of relay 8, right-hand alternate contact of relay 17, normal contact of relay 14 and upper alternate contact of relay 9 to ground. Relay 8, in operating, establishes a locking circuit for itself through its left-hand alternate contact, normal contact of relay 14 and upper alternate contact of relay 9. The operation of relay 17 short circuits the winding of, and prevents the operation of 95 ringing relay 16, whereby ringing current is prevented from being connected to a busy line to which the trunk circuit has been connected. The operation of relay 8 also removes a short circuit from the winding of 100 a high-resistance relay 26 effacing the lamp 7. The relay 26 also operates opening its contact which is in series with the right-hand winding of relay 6 and the lower contact of supervisory relay 21, so that the resistance in circuit with relay 22 is increased 105 causing the release of relay 22 to light the calling supervisory lamp 5. The operation of relay 8 also connects an interrupter 27 and a low-resistance relay 28 in parallel 110 with the high-resistance relay 26. Relay 26 will, thereupon, due to the rotation of the interrupter 27, be intermittently shunted by the low-resistance relay 28, and when so shunted it releases its armature, thereby 115 closing its contact to cause the decrease of the resistance in circuit with the supervisory relay 22, which thereupon operates to efface the supervisory lamp 5. The calling supervisory lamp 5 is thereby intermittently 120 lighted whenever the plug of the trunk circuit is connected with a busy line, and serves as a signal to the originating operator indicating that fact. The rotation of interrupter 27 also causes the intermittent operation of the low-resistance relay 28 which, when operated, connects an interrupter 125 30 in circuit with a winding 31 of an induction coil in the terminating operator's telephone set. This produces a series of clicks 130

in the operator's receiver, indicating to this terminating operator that the trunk circuit has been connected with the busy line. The intermittent inclusion of the low-resistance 5 relay 28 in parallel with the high-resistance relay 26 causes the intermittent lighting of the trunk supervisory lamp 7 which also serves as a signal to the terminating operator that the plug of the trunk circuit has 10 been connected with a busy line.

What is claimed is:

1. A telephone exchange system comprising a trunk circuit extending from a first to a second central office, a cord circuit at 15 the first central office connected with the trunk circuit, a signaling device in the trunk circuit and located at the second central office, telephone lines terminating at the second central office, a supervisory relay in the 20 trunk circuit energized upon connection thereof with a busy line over a circuit including the contacts of the switchhook, and apparatus controlled by the supervisory relay for causing the intermittent operation 25 of the signaling device.

2. A telephone exchange system comprising a trunk circuit extending from a first to a second central office, a cord circuit at the first central office connected with the 30 trunk circuit, a signaling device in the trunk circuit and located at the second central office, telephone lines terminating at the second central office, a supervisory relay in the 35 trunk circuit energized upon connection thereof with a busy line over a circuit including the contacts of the switchhook, a relay controlling the signaling device, and interrupter mechanism controlled by, and brought into circuit relation with the control relay upon the operation of, the supervisory relay to cause the intermittent operation 40 of the signaling device.

3. A telephone exchange system comprising a trunk circuit extending from a first to a second central office, a cord circuit at 45 the first central office connected with the trunk circuit, a signaling device in the trunk

circuit and located at the second central office, a signaling device in the cord circuit, telephone lines terminating at the second 50 central office, a supervisory relay in the trunk circuit energized upon connection thereof with a busy line over a circuit including the contacts of the switchhook, a relay controlling both signaling devices, and 55 interrupter mechanism controlled by the supervisory relay and coöperating with the control relay to cause the intermittent operation of both signaling devices.

4. A telephone exchange system comprising a trunk circuit extending from a first to a second central office, telephone lines terminating at said second central office, a sleeve relay associated with the trunk responsive to the connection of the trunk with 60 any line, a ringing relay normally controlled by such sleeve relay for connecting a source of ringing current to the connected line, a supervisory relay responsive upon the connection of the trunk with a closed line, a 65 trip relay responsive upon the closure of an open line, and a relay controlled by the supervisory and trip relays to disable the ringing relay.

5. A telephone exchange system comprising 75 a trunk circuit extending from a first to a second central office, a cord circuit at the first central office connected with the trunk circuit, lines terminating in the second central office, a source of ringing current 80 and a ringing relay associated with the trunk circuit, a supervisory relay included in such trunk circuit responsive to the connection of the trunk with a busy line, and means controlled by said supervisory relay 85 for disabling the ringing relay and for intermittently operating a signal associated with the cord circuit at the second central office.

In witness whereof, I hereunto subscribe 90 my name this 22d day of September, A. D., 1916.

HENRY P. CLAUSEN.
